DENTAL IMPRESSION PARTING TOOL

Louis Kalvin, New York, N. Y.

Application August 10, 1934, Serial No. 739,225

6 Claims. (Cl. 32—40)

This invention relates to parting tools useful in deeply scoring or slotting the partially set plaster or other composition in the course of taking dental impressions, so as to facilitate the separation of such impressions into predetermined segments along definite parting lines.

Supporting trays to hold the plaster in the act of applying to the dental arch are already known, in which grooves or ridges are formed in the tray for weakening the plaster impression along those lines on which it is to be parted. Where the denture is incomplete, the space where teeth are missing results in a solid wall of plaster into which such "parting partition ridges" do not penetrate sufficiently deep to ensure the breaking of the impression on the predetermined line.

The general purpose of the present invention is to provide a tool or instrument by which the plaster, at portions where teeth are missing, may be supplementally treated to produce or extend the parting groove sufficiently deep to ensure the parting of the cast on the desired line. Essentially, the device employs a loop-formed member which may readily be passed through a slotted portion of the tray, so as to penetrate the partially set plaster where teeth are missing, and moved transversely to form a definite groove or cleavage space and ensure the parting of the impression along the desired line. To facilitate the use of this loop-formed member, the invention comprises in its preferred embodiment a special holder by which the tool may be adjusted to convenient angles or positions with respect to a handle. A still further feature of importance in the preferred embodiment of the invention is an adjustable stop or depth gage by which the extent of penetration of the loop element may be adjusted and predetermined.

A preferred embodiment of the invention is illustrated by way of example in the accompanying drawing, in which

Figure 1 represents a perspective view showing the upper surface of a dental impression of an incomplete upper dental arch, as it would appear if removed unbroken from the subject to be reproduced.

Figure 2 is an underneath view of the tray showing the parting partition grooves and the slot through the tray at the portion where teeth are missing in the subject.

Figure 3 is a detail sectional elevation showing the loop member of the parting instrument inserted into the partially set plaster through the slot in the supporting tray.

Figure 4 is a side elevation of the complete parting tool in a preferred form.

Figure 5 is a vertical section thereof on the line 5—5 of Figure 4, with the parts somewhat enlarged, and

Figure 6 is a diagrammatic view illustrating the adaptability of the loop member to follow a curved slot in the supporting tray.

Referring in detail to said drawing, 10 indicates a barrel or handle formed at one end with the flaring socket 11 to receive the draw-in chuck or collet 12 which is moved inwardly or outwardly by operating the knurled thumb nut 13 on the end of rod 14, as clearly shown in Figure 5. The collet 12 is in the form of a tubular member longitudinally split or slotted on one or a plurality of lines extending part way of its length, and is shaped to receive the ball head 15 from which extends the neck 16 terminating in a cross-bar 17 in which are mounted the two ends of a looped wire 18. A knurled-headed stop screw 19 is adjustably threaded into the neck and ball members so as to be adjusted inwardly and outwardly within the loop member 18 for the purpose of varying the distance between the head of the stop screw and the end of the loop.

The construction described admits of the loop member 18 being set at varying angles with respect to the handle axis, by loosening the engagement of the collet 12 with the head 15 and shifting the loop into the desired position, as indicated by the dotted lines in Figure 4. The loop may be turned on its own axis in any of its angular positions with respect to the handle axis, and it will thus be apparent that a substantially universal adjustment of the loop with respect to the handle is provided. One or more of the slots provided in the collet may be sufficiently wide to admit of the neck portion 16 being moved into a position at right angles to the handle axis, or even lower if desired, or suitable recesses or apertures may be specially formed in the collet member to serve this purpose. The embodiment illustrated shows such an aperture in the form of an enlargement 20 of one of the longitudinal slots of the collet.

By referring to Figures 2, 3 and 6, it will be understood that in use the loop member 18 is projected through a slot 21 formed in the tray 22 which holds the plaster, to a depth depending upon the adjustment of the stop screw 19 which abuts against the bottom of the tray and thus limits the depth of penetration into the partially set plaster. Having inserted the loop member 18 into the plaster, the implement may then be

5 moved along the slot 21, whose length has been selected to conform with the length of the space where teeth are missing. By this movement the plaster is separated over a predetermined length 10 and at a predetermined depth, the instrument being then withdrawn and the plaster being allowed to set in this condition. As shown in Figure 6, the loop form of construction employed admits of the parting tool following a curved line without undue resistance, and without any substantial displacement of plaster beyond the immediate vicinity of the groove which is being formed. Since the slot 21 may be formed within the line of the parting partition ridge 15 indicated in Figure 2 at 23, the deep groove formed in the plaster by the parting tool will be a continuation of the shallow grooves formed in the plaster by the parting partition ridges of the tray.

20 The length of the slot 21 and the position of the stop screw 19 are so chosen that the molding surface of the plaster is not disturbed by the parting tool coming in contact with either the teeth or with the gum where teeth are lacking.

25 As shown in Figure 1, space 24, which represents a molding space of the gum surface between the tooth impressions 25, 26, is intact, although the plaster beneath the surface 24 may be deeply grooved, as shown at 25 in Figure 3.

30 By adjustment of the position of loop 18 with respect to the handle 10, as already described, the implement is readily accommodated in use to substantially any part of the mouth where teeth may be missing.

35 While the construction of the various parts has been particularly designed with a view to their mutual cooperation in the performance of the function intended, they are susceptible to useful application without necessarily following 40 the particular details of construction shown. For example, the stop member 19 and the adjustable head mounting with respect to the handle may find useful application in conjunction with modified forms of parting elements substituted for the loop 18 herein shown. Thus a 45 single pin or a pair of pins, representing one or both sides of the loop, may in many respects serve a useful purpose in an instrument for this class of work, and the stop member 19, on the other hand, may be omitted, or some other construction of stop member substituted therefor. In its preferred form, however, the inven-

tion comprises the combination of these various forms of elements cooperating substantially in the manner described. The continuous or uninterrupted loop of wire 18, having a curved outer contour and firmly secured at its ends in the cross-bar 17, provides a good rigid construction with a small amount of surface in contact with the plaster, and hence has very little tendency to drag or be deflected from its intended course while forming the deep groove within the partially set plaster. 5

I claim:-

1. A parting tool for dental impressions, comprising a loop member adapted to pass through a slit in a supporting tray and penetrate the partially set plaster, and a stop member for abutting against the tray and arresting the loop member at a predetermined depth of penetration. 15

2. A parting tool for dental impressions, comprising a loop member adapted to pass through a slit in a supporting tray for penetrating the partially set plaster, and a handle in which said loop member is adjustably secured. 20

3. A parting tool for dental impressions, comprising a loop member for penetrating the partially set plaster, and a stop member disposed within said loop member for limiting such penetration to a predetermined depth. 25

4. A parting tool for dental impressions, comprising a member for penetrating the partially set plaster, said member having an open space between its lateral edges, and an adjustable stop member disposed within the open space of said penetrating member for limiting the depth of such penetration. 30

5. A parting tool for dental impressions, comprising a ball member, a wire member projecting therefrom, and a handle member having a draw-in collet for adjustably holding said ball member in variable angular relations with respect to the handle axis. 40

6. A parting tool for dental impressions, comprising a wire member adapted to penetrate the partially set plaster, a ball member having a neck portion with cross-bar in which the ends of said wire member are mounted, and a handle having a draw-in collet engaging said ball member and recessed to receive the neck portion of said ball member in the angular adjustment of the wire member with respect to the handle axis. 45 50
